John B. Ellena, Etiwanda, Calif., assignor to Ellena Brothers, Etiwanda, Calif., a corporation of California

Application January 23, 1950, Serial No. 7,433

Term of patent 14 years

(Cl. D58—8)

To all whom it may concern:

Be it known that I, John B. Ellena, residing at Etiwanda, in the county of San Bernardino, State of California, have invented a new, original, and ornamental Design for Bottle, of which the following is a specification, reference being had to the accompanying drawing, forming part thereof, in which:

Fig. 1 is a front elevational view of a bottle, showing my new design;

Fig. 2 is a rear elevational view thereof;

Fig. 3 is a top plan view thereof; and

Fig. 4 is a bottom plan view thereof.

I claim:

The ornamental design for a bottle, as shown.

JOHN B. ELLENA.
